UNITED STATES PATENT OFFICE.

EDWARD A. NIX, OF MONTREAL, QUEBEC, CANADA.

WEATHERPROOFING MEANS FOR WINDOW-SASHES.

1,391,003.

Specification of Letters Patent. Patented Sept. 20, 1921.

Application filed November 21, 1919. Serial No. 339,593.

To all whom it may concern:

Be it known that I, EDWARD A. NIX, a citizen of the United States, and resident of the city of Montreal, in the Province of 5 Quebec, Dominion of Canada, have invented certain new and useful Improvements in Weatherproofing Means for Window-Sashes; and I hereby declare that the following is a full, clear, and exact description thereof.

10 My invention relates to weatherproofing means for sliding window sashes particularly those of railway cars and has for its object to provide a weatherproofing means which will permit of the withdrawal of the 15 sash from its frame upon removal of the vertical guiding beads or stops. A further object of my invention is to provide a construction, the parts of which may be readily applied, which will not resist the opening 20 and closing of the sash to noticeable extent and will be substantially concealed from view when the sash is in place.

To this end my invention consists of the construction and arrangement of parts hereinafter described and pointed out in the 25 claims.

For full comprehension however, of my invention, reference must be had to the accompanying drawings in which similar 30 reference characters indicate the same parts and wherein:

Figure 1 is an elevation of a window equipped with my improved weatherproofing means illustrated partly in section;

35 Fig. 2 is a vertical sectional view taken on line 2—2 Fig. 1;

Fig. 3 is a horizontal sectional view taken on line 3—3 Fig. 2; and

40 Figs. 4 and 5 are detail fragmentary perspective views of the interengaging weather strips.

The frame of a window such as is commonly used in railway car construction is shown in the accompanying drawings and 45 includes side posts 3 and window sill 4, and inside, outside and parting or middle window-stops 5, 5^a and 5^b respectively, between which the inner and outer sashes 6 and 7 slide, the outside stops being permanently 50 fastened in place as component parts of the car body.

My improved weatherproofing means consists of a pair of vertically disposed metal strips 14 and 15, mounted respectively upon 55 the inner faces of the stiles, of sashes 6 and 7. Each of these strips is formed from a

flat blank one side edge of which is bent upon itself as at 16 in hook form to present a channel adapted to accommodate the bent-back edge of strips on the inner stop and 60 the parting strip respectively, a series of holes 18 being punched out throughout its length adjacent the opposite side edge to accommodate screws 19 for fastening it to the sash.

65 These strips are adapted to interengage with strips 20 and 21, each of the latter being formed from a wider blank than the strips 14 and 15 and of rectangular cross section presenting two sides 22 and 23, the 70 edge of the former being bent back upon itself in hook form as at 24. The sides 23 of these last-mentioned strips extend between the posts 3 and the inside window-stops 5 in one case, and the parting stops 5^b 75 in the other case, and are secured to the stops by screws 26, the stops and sashes being rabbeted as at 25 to accommodate their respective strips.

80 The hooked side 22 extends between the window-stops and the sash with its hook in interengagement with the hook of the strip on the sash.

85 With the construction and arrangement of parts it will be seen that by taking out the screws 30 which fasten each of the window-stops to the frame, the window-stop with its weather strip may be removed and the sash completely withdrawn without in any way disturbing the weather strips on their supporting members.

90 In order to weatherproof the top and the bottom edges of the sash, I attach a folded strip of soft rubber 50, to the top edge of the outside face of the top rail and to the 95 bottom edge of the outside face of the bottom rail of each sash by a relatively heavy metal retaining plate 51, secured in place by screws 52, the sashes being rabbeted for the purpose.

100 What I claim is as follows:

1. The combination with a window frame including side posts, vertical window-stops removably secured to said posts, and a window sash slidably mounted within the frame 105 and between the stops, of weather-proofing means consisting of a pair of strips one side edge of each of which is bent back upon itself in hook form to present a channel adapted to receive the bent-back edge of the other strip, means securing one strip upon the window sash and means securing the other 110

strip on one of said stops, said strips being constructed and arranged to permit the removal of said stop and its strip as a unit without disturbing the means securing either 5 of the strips in place and irrespective of the position of the window sash.

2. The combination with a window frame including a side post, a window sash, a window stop and means removably securing 10 the stop to the side post, of weather-proofing means consisting of a strip secured to the window sash at one side thereof and disposed parallel to the side post, said strip having one side edge bent back upon itself in hook- 15 form, the bent back position extending outwardly away from the side post, a second strip carried by the window stop in position

facing the first strip and having its outer side edge relatively to the side post bent back upon itself and toward the side post in hook-form and interlocking with the hooked portion of the first strip whereby the stop may be removed and replaced without disturbing the position of the strips relatively to their carrying parts and irrespective of the 20 position of the sash.

In testimony whereof I have signed my name to this specification in the presence of two witnesses.

EDWARD A. NIX.
